UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed March 26, 1924. Serial No. 701,987.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

10 My invention relates to lasts.

The object of my invention is to provide a resilient hinge and link construction which may be readily and easily manufactured and assembled, which will be strong enough to 15 have a long life and maintain its resiliency, and which will keep the last parts in their expanded or collapsed position.

It is my object to provide a novel form 20 of resilient link to be used either with or without resilient pins.

It is a further object to so arrange the mounting of this link that a line drawn between the centers of the points of attachment of the links to the last parts will pass 25 over the center about which the last parts move when the parts are moved from expanded to collapsed position or vice-versa.

Referring to the drawings:

Figure 1 is a section through the last 30 when it is in its expanded position.

Figure 2 is a section through the last in its contracted position.

Figure 3 is a section on the line 5—5 of Figure 1, showing the mounting of the links 35 on resilient pins.

Referring to the drawings in detail;

1 is the heel part of the last and 2 is the toe part. The heel part 1 has its upper face 3 which adjoins the face 4 of the toe part 40 of the last at an angle to the vertical. This face 3 terminates in a semicircular projection 5 which is received in a semicircular depression 6 in the toe part of the last, so that a knuckle joint is formed between the 45 parts. The parts are limited in their movement in one direction by the abutting surfaces 7 and are limited in their movement in the other direction by the abutting surfaces 3 and 4.

50 Each last half is provided with the respective adjacent cutaway portions 8 and 9 in which are located the V-shaped links 10. These links are mounted upon the respective pins 11 and 12 and are made of 55 some resilient material. The last halves are

cut away as at 13 and 14 to permit the flexing of these pins, upon which are mounted the links. It is also possible to use my special form of link with pins which are not 60 resilient.

It will be noted that the last parts are adapted to move about the center 15. This center 15 in Figure 1 is above a line drawn between the centers of the pins 11 and 12 and below that line in Figure 2.

The V-shaped links are composed of a pair of arms, the ends of which are riveted to one another at 16. The movement of the last parts over dead center will tend to spring the pins and also draw the arms of the links 70 towards one another so that the centers of the connection 16 will approach one another when this passage over dead center is made.

The pivotal point indicated on the drawings is only approximate, but it is accurate 75 sufficiently to illustrate the principle of construction, as the drawings are not drawn to scale. The fundamental idea is to have the line drawn between the centers of the points of attachment pass over the dead 80 center which in a sense is the equivalent of the pivotal point.

I desire to comprehend within my invention such modifications as may be necessary 85 to adapt it to varying conditions.

Having thus fully described my invention, what I claim as new and desire to secure by Letters Patent, is:

1. In combination in a last, a heel part, a toe part, a link connecting said parts 90 consisting of spaced members joined at the ends thereof, and means for attaching said link to the respective parts, said link being adapted upon movement of the last parts in the collapsing or expanding operation 95 to permit its spaced members to approach each other.

2. In combination in a last, a toe part, a heel part, said parts being adapted to rock on one another, a connecting means connecting said parts to one another having its central portions spaced from one another and its ends united, and an attaching means for said connecting means located in each part, said attaching means being adapted to 100 be flexed upon the movement of the parts.

3. In combination in a last, a heel part, a toe part, a connecting link consisting of oppositely disposed V-shaped portions, and means for connecting the base of said V- 110

shaped portions to the last parts whereby the arms of the V will be flexed and brought closer to one another upon the movement of the parts, in the course of the collapsing or expanding operation.

4. In combination in a last, a heel part, a toe part, a connecting link consisting of oppositely disposed V-shaped portions, and means for connecting the base of said V-shaped portions to the last parts whereby the arms of the V will be flexed and brought closer to one another upon the movement of the parts, said means for attachment of the link to the respective parts being resilient and being adapted to be flexed.
5. In combination in a last, a heel part, a toe part, a connecting link consisting of oppositely disposed V-shaped portions, means for connecting the base of said V-shaped portions to the last parts whereby the arms of the V will be flexed and brought closer to one another upon the movement of the parts, said means of attachment of the link to the respective parts being resilient and being adapted to be flexed, and a knuckle joint between said parts about which they rock.
6. In combination in a last, a heel part, a toe part, a connecting link consisting of oppositely disposed V-shaped portions, means for connecting the base of said V-shaped portions to the last parts whereby the arms of the V will be flexed and brought closer to one another upon the movement of the parts, said means of attachment of the link to the respective parts being resilient and being adapted to be flexed, and a knuckle joint between said parts about which they rock, the attaching means being so arranged that a line drawn between the centers of attachment will be below the hinged center of the last parts when they are in expanded position and above said center when they are in collapsed position.
7. In combination in a last, a heel part, a toe part, said parts being arranged to rock with respect to one another, a pair of oppositely disposed V-shaped connecting plates, the free ends of which are riveted to one

another and the points of which are mounted on pins in the respective last parts, and pins in said last parts, said plates being adapted to flex during the collapsing or expanding operation.

8. In combination in a last, a heel part, a toe part, said parts being arranged to rock with respect to one another, a pair of oppositely disposed V-shaped connecting plates, the free ends of which are riveted to one another and the points of which are mounted on pins in the respective last parts, and pins in said last parts, said pins being resilient and said last parts being cut away to permit the pins flexing.

9. In combination in a last, a heel part, a toe part, means for permitting said parts to rock on one another, centrally located cutaway portions in said last parts having their open ends adjacent to one another, oppositely disposed V-shaped plates located in said cutaway portions, the free ends of which are riveted to one another and the bases of which are mounted on transverse pins located in the last parts and intersecting said cutaway portions, and transverse pins, said free ends being adapted to approach one another when strain is applied to said plates.

10. In combination in a last, a heel part, a toe part, means for permitting said parts to rock on one another, centrally located cutaway portions in said last parts having their open ends adjacent to one another, oppositely disposed V-shaped plates located in said cutaway portions, the free ends of which are riveted to one another and the bases of which are mounted on transverse pins located in the last parts and intersecting said cutaway portions, and transverse pins, said last parts being made of resilient material and adapted to compress to a limited degree, said plates being adapted to flex during the expanding or collapsing operation.

In testimony whereof, I affix my signature.

GEORGE CLAUSING.
